UNITED STATES PATENT OFFICE

128,041

DESIGN FOR A HAND GRIP FOR A LAWN MOWER HANDLE

Truman B. Funk, Jackson, Mich., assignor to Yard-Man, Inc., Jackson, Mich., a corporation of Michigan

Application April 24, 1940, Serial No. 91,899

Term of patent 14 years

To all whom it may concern:

Be it known that I, Truman B. Funk, a citizen of the United States, residing at Jackson, in the county of Jackson and State of Michigan, have invented a new, original, and ornamental Design for a Hand Grip for a Lawn Mower Handle, of which the following is a specification, reference being had to the accompanying drawing, forming part thereof.

The single figure in the drawing is an elevational view of a hand grip for lawn mower handle showing my new design.

The hand grip member is circular in cross section throughout its length.

I claim:

The ornamental design for a hand grip for a lawn mower handle, substantially as shown and described.

TRUMAN B. FUNK.
